UNITED STATES PATENT OFFICE.

OTTO H. KRUEGER, OF LOS ANGELES, CALIFORNIA.

TYPE-WRITER ATTACHMENT.

1,285,242.

Specification of Letters Patent. Patented Nov. 19, 1918.

Application filed July 9, 1917. Serial No. 179,410.

To all whom it may concern:

Be it known that I, OTTO H. KRUEGER, a subject of the Emperor of Germany, residing at Los Angeles, in the county of Los Angeles and State of California, have invented a new and useful Type-Writer Attachment, of which the following is a specification.

This invention relates to typewriter attachments and more particularly to attachments for holding copies on the typewriter for the purpose of copying the same.

The object of this invention is to hold the original manuscript or any paper which is to be copied above and close to the paper to be written so as to hold and bring letter above letter, figure above figure and space above space of the original paper in relation to the newly written paper.

Another object is to provide means by which the original paper is held close to the new paper to be copied from the original.

Another object is to provide means by which the original paper is shifted automatically with the paper shifting mechanism on a typewriter.

Another object is to hold the original paper free from and above the paper written on the typewriter and copied from the original paper.

Another object is to provide shifting mechanism on the attachment similar to the shifting mechanism on the typewriter so as to allow the shifting of the original paper above the newly written paper in accordance with the advancing of the newly written paper separate from the shifting of the newly written paper, shifted by the mechanism of the typewriter.

Another object is to cover the writing of the original paper except for a suitable number of words so as to make it easy to compare the words of the original paper with the words of the newly written paper.

Another object is to provide scales near the words of the original paper and similar scales near the words of the newly written paper so as to automatically check up the letters, figures and spaces of the original paper with the letters, figures and spaces of the newly written paper to the minute details.

Other objects will appear from the following and accompanying papers.

In the drawing —

55

Figure 1 is a front elevation of an assembly of my device.

Fig. 2 is an end elevation of the device in Fig. 1.

Fig. 3 is a fragmentary sectional view on line 3—3 of Fig. 1.

Fig. 4 is a fragmentary elevation of the frame with roller engaging mechanism.

Fig. 5 is a detail side elevation of the spring for holding the reading plate and 65 checking plate in a desired position, to be secured to the main frame 5.

Fig. 6 is a fragmentary perspective view, illustrating the engaging of the lower ends of the main frame over the shaft of the 70 platen, such shaft and platen as well as a fragmentary perspective view of a typewriter being shown in dotted lines.

5 designates the main frame suitably shaped at its lower end 6 to engage over 75 the shaft 7 of the main roller 8 in a typewriter 52, and also constructed to allow the attachment of suitable extra plates 9 to make the frame applicable to the different makes of typewriters. In Fig. 2, the lower 80 end 6 of the main frame is formed hook-like to hook over the shaft 7 of the typewriter-roller 8 from the front, the extension end 10 projecting toward the rear of the typewriter having a suitable number of 85 threaded holes 11 for screws, by which in combination with the small plate 9 the main frame 5 is secured to the typewriter. The plate 9 is provided with slots or notches 12 allowing a shifting in a suitable direction 90 to bring the slot, notch or cut out 13 close to a rod 51 or suitable screws on the typewriter thereby locking the plate and therewith the main frame to the typewriter, as will easily be understood, there being always 95 rods or screws rearwardly of the main roller or platen within the frame work of the typewriter. And it will also easily be understood that other means may be used as long as the frame 5 can thereby be held 100 on the typewriter in a similar manner.

A rod, as indicated at 51 in Fig. 2, is on certain types of Underwood typewriters a short distance behind the platen parallel to

the platen. Other typewriters have rods or screws or other suitable parts in their framework near the platen which make it necessary that the extension end 10 be constructed different for different types or makes of typewriters, or that at least other means be provided for the small plates 9 for different typewriters. The main thing is to bring always the copy-holding rollers parallel to the platen of the typewriter to properly and evenly engage with the whole surface of the platen to insure the parallel shifting of the copy, held between the copy-holding rollers, in suitable relation with the shifting of the newly written paper on the platen. To this end, I prefer the hook-shaped ends 6 of the main frame 5 to engage over the shafts of the platen of the typewriter as described, having the slots or guideways 14 radially to the platen in such suitable alignment with hook-shaped ends of the frame 5. In certain Underwood typewriters, which have the rod 51, the hook-shaped ends are engaged over the shafts 7 of the platen, bringing the extension ends 10 to rest on the rod 51. The small plate 9 is then slipped from below over the rod 51 for holding the extension ends toward the rod by disposing screws in suitably positioned holes 11 in the extension ends 10. A suitable number of holes 11 are provided to suit the conditions of different typewriters, and, by providing suitable plates, clamps, or other suitable engaging members to suit the conditions of different typewriters, it will easily be understood that the hook-shaped ends 6 can always be engaged to the shafts of the platen of any typewriter by their extension ends 10.

The slots or guideways 14 are suitably provided in the main frame for the holding rollers 15 and 16, allowing the shafts of the rollers to slide toward the main roller 8.

The blank sheet of paper 17 is placed on the main roller 8 of the typewriter in the usual manner, while the letter or paper 18 from which a copy is to be made, is placed over the roller 15. The roller 16 serves in this device as a shifting transmitter and direction giving medium only. The spring 19, secured at 20 to the main frame and at 21 to the distance piece or member 22, holds the rollers 15 and 16 pressed toward the main roller 8 of the typewriter and thereby causes the transmission of the motion of the main roller to the rollers 15 and 16. A shifting of the main roller 8 from the finished line to a line below for the next line to be written causes also the rollers 15 and 16 to move a similar distance so as to bring another line of the original paper toward the front on the roller 15.

To bring the line to be copied out more clearly and distinctly from the whole writing of the original letter, held on the roller

15, a reading plate 23 is swingably mounted above the roller 15. The reading plate is provided with a slot 24 of suitable width and length to show just the desired number of words or figures so as to make it easy to check these few words or figures with the words and figures appearing on the newly written paper, on the main roller 8 of the typewriter. To make the checking easier yet, a checking plate 25 is provided above the main roller 8 hanging down over the roller 8 so as to show just one line or any other suitable number of lines which can easily and quickly be read and compared with the words seen within the slot 24, in the reading plate 23, while writing and copying from the original paper on the roller 15. Scales 26 are provided on the reading plate 23 and corresponding scales 27 on the checking plate 25 near the main roller 8, showing the same letter or figure near the corresponding scale-marks.

In case that the copy, to be made, is to be written in shorter lines than the original paper, the original paper naturally should not be shifted at the same moment when the short line of the newly written paper is finished; therefore I provide a disengaging mechanism lifting the holding rollers 15 and 16 from the main roller 8 allowing the main roller 8 to turn in the usual manner, by the well known mechanism on typewriters not shown in the drawing, while the holding rollers 15 and 16 are turned by an extra mechanism whenever all the words and figures of the longer lines of the original paper are copied over to the newly written paper on the main roller 8. In Fig. 1, a knob 28 is provided on the shaft 29 of the roller 15 for turning this roller manually, and a catching lever 30 and a ratchet pawl 31 engage with the ratchet wheel 32 for holding the roller in position so as to show the writing of the original paper within the slot 24 of the reading plate 23. Such catching lever 30 and ratchet pawl 31, of course, engage only when the rollers with the ratchet wheel have been brought to the upper position as described above, while, the rollers in position receiving their rotating motion directly from the main platen, the ratchet is naturally a short distance below the catching lever and ratchet pawl in the normal lower position of the rollers and ratchet wheel, as will easily be understood.

The roller 16 with the shaft 33 is turnably mounted in the lower ends 34 of the disengaging frame 35. The shaft 29 of the roller 15 and the extension ends 36 of the reading plate 23 are slidably mounted in the slots 38 of the disengaging frame 35. The reading plate 23 and the roller 15 are held at a suitable distance by the distance members 37 so as to hold the writing of the

original paper on about the middle of the roller 15 and within the slot 24 of the reading plate 23. The shaft 33 of the roller 16, the shaft 29 of the roller 15 and the extension ends 36 of the reading plate 23 are also 5 slidably mounted in the slots 14 of the main frame 5.

To disengage the holding rollers 15 and 16 from the main roller 8 for the purpose 10 described above, the disengaging frame 35 is lifted until the catch 39 engages the frame 35 holding the frame in this suspended position. The catch 39 is swingably mounted on the main frame 5 by the pin plate 40.

15 As soon as the catch is released, the disengaging frame 35 is pulled down into its engaging position in relation with the main roller and the holding rollers 15 and 16 by the springs 19, as described above.

20 If the reading and checking plates are not desired close to the rollers, they can be set by suitably shaped spring members 45, having suitably shaped recesses 43 and 44, allowing a setting of the plates from the 25 lower position 41 to the upper position 42 just as desired.

Such spring members can easily be attached to the frames close to the edges of the reading and checking plates, as will 30 easily be understood.

Having thus described my invention, I claim:

1. In a copy checking device of the class described a frame having means for removably engaging the shaft near both ends of the main roller or platen of a typewriter and projecting from such engaging points radially in relation to the platen, both ends 35 of the frame having slots extending from near the engaging points to a suitable extent radially in relation to the platen, and copy holding rollers turnably disposed within the frame and engaging with the slots for sliding movement radially in relation to the 40 main roller or platen, the longitudinal axis 45

of the copy holding rollers being parallel to the axis of the platen.

2. In a copy checking device of the class described a stationary frame having means for removably engaging the shaft near both 50 ends of the platen of the typewriter and having slots from near the engaging points extending to a suitable extent radially to the platen forming the stationary frame for the copy checking device, copy holding rollers having shafts disposed through the slots in the stationary frame, and a movable frame having slots parallel to the slots in the stationary frame for slidably engaging over the shafts on the copy holding rollers 55 adapted to hold the copy holding rollers out of engagement with the platen of the typewriter.

3. In a copy checking device of the class described a frame comprising two parallel 60 guide members each having a guideway parallel to a guideway in the other, copy-holding rollers turnably and slidably mounted in the guideways of the frame, the frame having also means for removably engaging a 65 typewriter at any suitable point for bringing the guideways in the frame into radial relation to the axis of the platen of the typewriter, the guideways being of suitable 70 length and design to allow one of the copy-holding rollers to rest on the platen of the typewriter parallel to the platen and allowing another roller to rest on the first named roller parallel to the first named roller the guideways also adapted to allow 75 a shifting of the copy-holding rollers to a suitable extent to be out of engagement with the platen.

In testimony whereof I have hereunto set my hand at Los Angeles, California.

OTTO H. KRUEGER.
